DESIGN.

J. H. WHIPPLE.

HOOD.

Patented Apr. 5, 1887.

No. 17,246.

Fig. 1.

Fig. 2.

UNITED STATES PATENT OFFICE.

JOSEPH H. WHIPPLE, OF BATTLE CREEK, MICHIGAN.

DESIGN FOR A HOOD.

SPECIFICATION forming part of Design No. 17,246, dated April 5, 1887.

Application filed November 17, 1886. Serial No. 219,215. Term of patent 3½ years.

To all whom it may concern:

Be it known that I, JOSEPH H. WHIPPLE, a citizen of the United States, residing at Battle Creek, in the county of Calhoun and State of Michigan, have invented and produced a new and original Design for Hoods; and I do declare the following to be a full, clear, and exact description of the same, reference being had to the accompanying photographic representation, forming a part thereof.

The features of this design in knit hoods consist in the ornamentation thereof.

The design is illustrated in the accompanying photographic representation, in which—
15 Figure 1 is a side and Fig. 2 a front view of the hood.

In shape the hood is at least as high as its width at the base. The base of the hood has an upturned or folded plait, A, of substantially the proportional width shown. The 20 hood curves uniformly from the base converg-

ingly to the apex of the hood. On one side of the hood is ornamented by a plume, B. This plume covers the greater part of one side of the hood, extending up above the apex and 25 extending downward partly over the plait A. A bow, C, is located upon the lower part of this plume, and above the bow C is a half-bow, D.

I claim as my invention—

In a design for a hood, the hood having an upturned plait at the bottom, a plume covering the greater part of one side of the hood, and a bow upon the plume, substantially as shown.

In testimony whereof I affix my signature in presence of two witnesses.

JOSEPH H. WHIPPLE.
